UNITED STATES PATENT OFFICE.

JEAN ALBERT HARDY, OF LEVALLOIS-PERRET, FRANCE.

TWO-STROKE-CYCLE EXPLOSION-ENGINE.

1,168,199.

Specification of Letters Patent. Patented Jan. 11, 1916.

Application filed November 17, 1913. Serial No. 801,556.

To all whom it may concern:

Be it known that I, JEAN ALBERT HARDY, a citizen of the Republic of France, and residing at 21 Rue Rivay, Levallois-Perret, 5 Department of Seine, France, have invented a certain new and useful Improvement in Two-Stroke-Cycle Explosion-Engines, of which the following is a specification.

This invention relates to two-stroke cycle 10 explosion engines in which the distribution is effected by a sleeve-extension of the working piston and in which the sleeve in question carries an annular piston intended to compress the scavenging gases.

15 The invention has for object an engine of this type in which the sleeve-extension of the working pistons is provided with two annular pistons allowing of compressing fresh air on one hand and the carbureted mixture on 20 the other hand, so as to insure a double scavenging of the working cylinder.

The object of the invention is represented by way of example upon the annexed drawing which shows:

25 Figure 1 an axial section of a single cylinder engine and its piston. Fig. 2 a transverse section of the sleeve upon line 2—2 of Fig. 1 at the level of the ports for admitting the carbureted mixture. Fig. 3 a transverse 30 section on line 3—3 of Fig. 1 at the level of the exhaust-ports. Fig. 4 an axial section of the cylinders of a two-cylinder engine constructed in accordance with the invention. Fig. 5 a transverse section on line 5—5 of Fig. 4. Fig. 6 a transverse section on line 35 6—6 of Fig. 4, at the level of the exhaust-ports. Fig. 7 a section through the distributor on line 7—7 of Fig. 5. Fig. 8 a rear view according to the arrow α in Fig. 5, the front 40 wall of the distribution cylinder being removed. Fig. 9 a front view along the arrow γ in Fig. 5, the cover plate being removed.

The engine consists of a cylinder a and a 45 piston b , the latter having an extension in the form of a sleeve c which slides around a fixed piston d . This sleeve carries two annular pistons e and f fitting in pump-casings e' and f' which are of different bores. The 50 three staged pump-casings e' and f' so formed are respectively intended, e' for the scavenging air, e' for the carbureted mixture, while f' which does not serve for the scavenging, may be placed in communication with the crank case or else be used as a special pump as will be seen hereafter.

The admissions of air, on the one hand, and of carbureted mixture on the other hand, take place automatically in the pump-casings e' and e' respectively. There is provided for this purpose in the wall of the 60 fixed piston d an opening c^2 which communicates with the exterior air through the hollow central portion of the fixed piston d ; this opening c^2 is uncovered at the upper end of the stroke of the piston b by openings 65 c^3 formed in the wall of the sleeve c above the annular piston e . Similarly there is provided in the wall of the fixed piston d an opening e^2 which communicates with the carburetor through a passage d' formed in the 70 interior of this piston. The opening e^2 is uncovered at the upper end of the stroke of the piston b by openings e^3 formed in the wall of the sleeve c above the annular piston e . The openings e^3 do not extend around the 75 whole circumference of the sleeve but the blank portion e^4 (Fig. 2) registers with the port c^2 thus preventing the sucking of air through this port into the chamber e^2 for the explosive mixture when the ports e^3 arrive 80 at the level of the port c^2 . The sleeve c is moreover provided, for the escape of the burnt gases, with orifices g which when the piston is at the bottom of its stroke register with ports opening to an exhaust collector h cast with the cylinder. This collector is closed externally by a brass or steel ribbon h' which is clamped upon an asbestos lining or gasket h^2 by means of screws h^3 (see especially Fig. 3).

In order to insure a rapid evacuation of the exhaust gases and an efficacious scavenging of the cylinder by the fresh gases, there are given to the head of the working piston b and to the exhaust collector h , on the one hand and to the head d^3 of the fixed piston d and to the inlet ports e^3 and c^3 , on the other hand, the arrangements shown in Figs. 3 and 2. The ribs g' which separate the exhaust ports g and connect the piston b to the sleeve c are formed in the shape of vanes (Fig. 3) in front of which are the fixed vanes h^4 situated within the exhaust collector h . In these conditions, the gaseous molecules escape in such a manner that there is produced neither sudden change of direction nor shock against the walls. Moreover in order to avoid eddies and back pressure in the exhaust collector, the exhaust port g 100 which is nearest to the exit from the exhaust 105 110

collector h may be arranged so that it is uncovered a little before the others. There are likewise provided upon the head d^3 of the fixed piston d spiral ribs or grooves d^2 which 5 are so arranged as to impart to the entering air or explosive mixture a swirling motion either in the same direction as that imparted to the exhaust by the guide vanes g^1, h^4 , in case a quick scavenge is desired or in the 10 opposite direction if it is desired to prevent loss of the freshly admitted explosive mixture.

An igniter i , in the form of a spark-plug or tube, is arranged on the side of the engine 15 in a small chamber i' of which the opening is uncovered by the orifices g when the piston comes near the top of its stroke.

The operation of the engine is as follows: During the upward movements of the engine piston b , the annular pistons e and f 20 create a partial vacuum in the pump-casings c' and e' which become filled, the one with air, the other with carbureted mixture, when the ports c^3 and e^3 come in front of the openings c^2 and e^2 . During the downward stroke 25 of the engine piston, the air and the mixture are compressed in their respective pump-casings. The moment the ports c^3 are uncovered by the edge of the fixed piston d , 30 the air compressed in the pump casing c' is driven into the cylinder and scavenges the burnt gases which escape through the ports g into exhaust collector h ; a little later, the orifices e^3 are in turn uncovered by 35 the edge of the fixed piston d , in such a way that the carbureted mixture compressed in the pump-casing e' fills the cylinder driving out the fresh air before it.

As already mentioned, the upper pump-casing f' can be connected to the crank case 40 of the engine by a passage f^2 . It may also be employed as an independent air-pump. The distribution can be effected either by a valve or other distributor or automatically 45 by means of an arrangement similar to that of the pump-casings c' and e' . This air-pump can serve for compressing air for the use of the engine (starting, injection of liquid fuel, temporary use as compressed air 50 motor for increasing the power of the engine, etc.). It can likewise be employed for external uses and form an engine pump group or self-contained unit of high efficiency, all intermediate transmissions being suppressed. This group can be utilized as 55 air-compressor, pump or aspirator for vacuum cleaning, etc. In order to increase the capacity of the pump, it suffices to increase the diameter of the annular piston f , but in this case it is necessary to use only 60 a part of the stroke of the pump casing e' , so as to deliver to the working cylinder only the desired volume of carbureted mixture; this may be done by lowering the opening c^2 . 65 Figs. 4 to 9 relate to the application of

the invention to a two-cylinder engine of which the pistons are set at 180 degrees. In this case the pump-casings c' and f' have the same bore; the lower pump casings c' serve as air-pumps as before and the upper bodies f' serve as mixture-pumps. The parts e' comprised between the annular pistons e and f serve to connect the ports e^2 delivering the carbureted mixture with the ports e^3 formed in the sleeves c above the annular 70 pistons e . The pump casing f' of the cylinder on the right is in constant communication with the intermediate space e' of the cylinder on the left, and conversely the pump-casing f' of the left-hand cylinder 75 constantly communicates with the intermediate space e' of the right hand cylinder. For this purpose the cylinders are provided with ports f^{20} and e^2 which communicate with a box f^3 (see Figs. 5 and 9) placed on 80 the front of the cylinders and closed by a cover f^4 ; the ports f^{20} on the right communicate with the ports e^2 on the left by the interior of the box, while the ports f^{20} on the left communicate with the orifices e^2 on the 85 right by the interior of the cover. Upon the opposite face of the cylinders is placed the single distributor which serves the two cylinders. The distributor is formed by a piston k (Fig. 7) which is connected by a rod 90 k' to an eccentric (not shown) fixed at the center of the engine crankshaft. This piston k reciprocates in a cylinder l which is provided at its lower part with ports l' and l^2 (Fig. 8) for the admission of air to the 95 cylinders and at its upper part with ports l^3 and l^4 for the admission of carbureted gases to the pump casings f' ; moreover this cylinder has openings l^5 near its center 100 communicating freely with the exterior, 105 and the top l^6 of the cylinder is connected to the carbureter (not shown). The orifices l' which correspond to the right-hand cylinder and the orifices l^2 which correspond to the left-hand cylinder 110 are offset by a certain height (see Fig. 8); the same applies to the orifices l^3 of the right-hand cylinder and l^4 of the left-hand cylinder. Passages l^7 and l^8 respectively 115 connect these orifices into the cylinders at the same height as the orifices l' and l^3 . The distributor piston k is divided by the diaphragm k^4 into two chambers, of which the upper viz. k^2 always communicates with the carbureter and the lower k^3 with the outer air by elongated openings k^5 situated in front of the openings l^5 in the cylinder l . This piston also carries in the part k^2 orifices k^6 for admitting the mixture and in its portion k^3 orifices k^7 for the admission of air. 120 These orifices k^6 and k^7 uncover the orifices l' and l^4 respectively when the distributor piston k is at the bottom of its stroke and the orifices l^2 and l^3 when the said piston is 125 at the top of its stroke. 130

At *i* are placed the igniters.

The working of the engine is the following:—During the upward stroke of the engine piston *b* of the left-hand cylinder (Fig. 4), the annular piston *e* creates a depression in the pump casing *c'* of this cylinder while the annular piston *f* (which is descending) of the right hand cylinder creates a depression in the pump-casing *f'* of the cylinder; 5 during this stroke, the distributor *k* places the left-hand pump casing *c'* and the right hand pump-casing *f'* in communication respectively with the exterior air and the carbureter, so these pump-casings are filled, 10 one with air, the other with carbureted mixture. But since the intermediate space *e'* of the left-hand cylinder is always in communication by the box *f²* with the pump-body *f'* of the right-hand cylinder, this 15 intermediate space *e'* is likewise filled with carbureted mixture. During the descending stroke of the left-hand piston *b* and therefore during the ascending stroke of the right-hand piston, the air is compressed in 20 the left-hand pump body *c'* and the mixture in the right-hand pump-body *f'*, that is to say also in the left-hand intermediate space *e'*. At the end of the descending stroke of the left-hand working piston, the 25 orifices *c³* and *e³* will be uncovered successively, and there will be produced as in the case of the single-cylinder engine a scavenging by fresh air and then an admission of carbureted mixture. The working is 30 evidently identical for the other cylinder of the engine.

As seen in Fig. 6, the engine pistons and the exhaust collector are provided with vanes for assisting the flow of the exhaust 35 gases and avoiding eddies.

What I claim and desire to secure by Letters Patent of the United States is:

1. In an internal combustion engine, an explosion cylinder and a piston working 40 therein, a sleeve extension for said piston, a pair of pump pistons spaced apart thereon, pump casings therefor, means for admitting air to one of said pump casings and an explosive mixture to the other, and ports in 45 said sleeve for admitting the compressed air and mixture independently to the explosion cylinder, substantially as described.

2. In an internal combustion engine, an explosion cylinder and a piston working 50 therein, a sleeve extension for said piston, a pair of pump pistons spaced apart thereon, pump casings therefor, means for admitting air to one of said pump casings and an explosive mixture to the other, and ports in said sleeve 55 for admitting the compressed air and mixture independently and in succession to the working cylinder, substantially as described.

3. In an internal combustion engine, an explosion cylinder and a piston working 60 therein, a sleeve extension for said piston,

a pair of pump pistons spaced apart thereon, pump casings therefor, said pump pistons and casing being of different diameter, means for admitting air to one of said pump casings and an explosive mixture to the 70 other, and ports in said sleeve for admitting the compressed air and mixture independently to the explosion cylinder, substantially as described.

4. In an internal combustion engine, an 75 explosion cylinder and a piston working therein, a sleeve extension on said piston, a pair of pump pistons of different diameter spaced apart thereon, adjacent pump casings opening to one another for said pump pistons, the working chamber for the pump piston of smaller diameter forming above the piston a compression chamber open to the working chamber of the piston of larger diameter, and means for admitting an explosive mixture to the working face of the piston of larger diameter and air to the working face of the smaller piston together with ports in said sleeve for admitting the compressed air and gas from the pump 80 chambers to the working cylinder.

5. In an internal combustion engine, an 85 explosion cylinder and a piston working therein, a sleeve extension on said piston, a pair of pump pistons of different diameter spaced apart thereon, adjacent pump casings opening to one another for said pistons, the working chamber for the pump piston of smaller diameter forming above the piston a compression chamber open to 90 the working chamber of the piston of larger diameter, and means for admitting an explosive mixture to the working face of the piston of larger diameter and air to the working face of the smaller piston, together with ports in said sleeve for admitting the compressed air and gas from the pump 95 chambers to the working cylinder in succession, first air then mixture, substantially as described.

6. In an internal combustion engine, a 100 working cylinder, a piston therein, a sleeve extension of said piston provided with a pair of pump pistons spaced apart, pump casings therefor, and ports above and below 105 one of said pistons opening from the pump chambers to the working cylinder at the end of the pump compression stroke, substantially as described.

7. In an internal combustion engine, a 110 working cylinder, a piston therein, a sleeve extension of said piston provided with a pair of pump pistons spaced apart, pump casings therefor, and ports above and below one of said pistons opening in succession from the 115 pump chambers to the working cylinder at the end of the pump compression stroke, substantially as described.

8. In an internal combustion engine, a 120 working cylinder, a piston therein, a sleeve 125

extension of said piston provided with a pair of pump pistons spaced apart, pump casings therefor, and ports above and below one of said pistons opening in succession from the pump chambers to the working cylinder at the end of the pump compression stroke, together with means for admitting air and explosive mixture to the respective pump chambers on the return stroke of said pump pistons.

9. In an internal combustion engine, a working cylinder, a piston therein, a sleeve extension of said piston provided with a pair of pump pistons spaced apart, pump casings therefor, and ports above and below one of said pistons, together with means for admitting air and explosive mixture respectively through said ports to the respective pump chambers on the return stroke of said pump pistons.

10. In an internal combustion engine, a working cylinder, a piston therein, a sleeve extension of said piston provided with a pair of pump pistons spaced apart thereon, pump casing therefor forming pump chambers in which a vacuum is produced during the return stroke of the motor piston, means for admitting air and explosive mixture respectively to the pump chambers toward the end of said return stroke of the motor piston and means for admitting said pump, compressed air and mixture independently from the pump chambers to the motor cylinder at the end of the working stroke of the motor piston.

11. In an internal combustion engine, a working cylinder, a piston therein, a sleeve extension of said piston provided with a pair of pump pistons spaced apart thereon, pump casings therefor forming pump chambers in which a vacuum is produced during the return stroke of the motor piston, means for admitting air and explosive mixture respectively to the pump chambers toward the end of said return stroke of the motor piston and means for admitting compressed air and mixture independently and in succession from the pump chambers to the motor cylinder at the end of the working stroke of the motor piston.

12. In an internal combustion engine, an explosion cylinder, a motor piston working therein, a sleeve extension therefor having a piston head and ports in the sleeve and on opposite sides of said piston head for ad-

mitting independently and in succession to the explosion cylinder, compressed air through one port and compressed explosive mixture through the other port, substantially as described.

13. In an internal combustion engine, an explosion cylinder, a motor piston working therein, a sleeve extension therefor and ports spaced apart on said sleeve opening in succession to the explosion cylinder at the end of the working stroke of its piston, chambers respectively communicating with said ports and means carried by said sleeve extension for forming therein respectively supplies of air and explosive mixture under pressure, substantially as described.

14. In an internal combustion engine, an explosion cylinder, and a piston working therein, a sleeve extension for said piston, a pair of pump pistons spaced apart on said sleeve, casing means forming a mid-chamber between the two pump pistons and two end chambers within which said pistons respectively work, means for separately admitting air and explosive mixture one to the mid-chamber between the pistons and the other to one of the end chambers, ports in said sleeve for admitting the air and explosive mixture from said chambers to the explosion cylinder, and a port opening to the other end chamber, for the purpose described.

15. In an internal combustion engine, an explosion cylinder, a conchoidal exhaust-collecting chamber communicating therewith and arcuate vanes for guiding the exhaust discharge into said collecting chamber from the explosion cylinder without sudden change of direction of the exhaust gases.

16. In an internal combustion engine, an explosion cylinder, a conchoidal exhaust-collecting chamber communicating therewith and arcuate vanes on the piston head and chamber casing for guiding the exhaust discharge into said collecting chamber from the explosion cylinder without sudden change of direction of the exhaust gases.

In testimony whereof I have signed my name to this specification, in the presence of two subscribing witnesses.

JEAN ALBERT HARDY.
